UNITED STATES PATENT OFFICE

148,414

DESIGN FOR A BROOCH OR SIMILAR ARTICLE

Nathan Gross, Brooklyn, N. Y.

Application June 11, 1946, Serial No. 130,606

Term of patent 3½ years

(Cl. D45—19)

To all whom it may concern:

Be it known that I, Nathan Gross, a citizen of the United States, residing at the Borough of Brooklyn, county of Kings, city and State of New York, have invented a new, original, and ornamental Design for a Brooch or Similar Article, of which the following is a specification, reference being had to the accompanying drawings, forming part thereof, wherein Fig. 1 is a front view of a brooch showing my new design and Fig. 2 is the left side view of Fig. 1.

I claim:

The ornamental design for a brooch or similar article, substantially as shown.

NATHAN GROSS.
